UNITED STATES PATENT OFFICE.

LUDWIG KÜHN, OF BERLIN, GERMANY, ASSIGNOR TO WESTINGHOUSE ELECTRIC & MANUFACTURING COMPANY, A CORPORATION OF PENNSYLVANIA.

RADIO SIGNALING SYSTEM.

Application filed August 26, 1921, Serial No. 495,738, and in Germany August 18, 1920.

(GRANTED UNDER THE PROVISIONS OF THE ACT OF MARCH 3, 1921, 41 STAT. L., 1313.)

This invention relates to radio communication systems, more particularly transmission systems employing vacuum tube oscillators which generate continuous waves modulated at an audible frequency. It has been shown previously that signals, particularly speech, can be transmitted by a vacuum tube oscillator in which the energy output is constant. To accomplish this, a modulator tube is employed the grid potential of which is varied in accordance with the speech frequency.

Instead of influencing the grid of the modulator tube by means of speech frequency, it is proposed by the present invention to influence the grid at an audible frequency which may be constant and not necessarily varied in accordance with speech. It is proposed to use a high frequency generator the output of which is used to vary the grid potential of the modulator tube. A key may be inserted in the output circuit of the audio-frequency generator to permit the sending of characters in any sequence desired. It is possible when using an audio-frequency current generator for the grid of the modulator tube, to rectify a portion of the output and use the rectified current as a source of energy for the plate circuits of both the oscillator and modulator tubes.

A clearer understanding of the invention may be had by reference to the following description of a preferred embodiment which is illustrated in the accompanying drawings. In these drawings there is shown a schematic arrangement of a vacuum tube oscillator the output of which is modulated by a modulator tube, the resistance of which is varied by impressing an audio-frequency potential on the grid.

Referring now to the drawing, a vacuum tube oscillator of the usual form is represented at 1 and its modulator tube is represented at 2. The modulator tube is connected to the oscillator tube in the well-known manner whereby the energy output of the oscillator

tube is maintained constant. The grid circuit of the modulator tube 2 is coupled by means of an audio-frequency transformer 6 to an audio-frequency alternator 3. A key 5 may be inserted in this circuit to permit the interruption of the wave train to form signals of any desired sequence. In order to obtain the necessary energy for the output circuits of the vacuum tubes, a portion of the 55 output of the alternator 3 is rectified by means of the vacuum tube rectifier 4, which has in series with its output circuit a choke coil 7.

The fundamental idea of the invention can 60 of course be used in a variety of ways. For example, the modulator tube may be influenced by a separate alternating current machine and the output circuits of the vacuum tubes may be supplied with energy from a 65 source of direct current.

I claim:

1. In a radio transmitting system, a vacuum tube oscillator having an anode, a vacuum tube modulator having an anode and a 70 grid, a conductive connection between said anodes, a rectifier having an output circuit connected to said anodes and an input circuit energized from a source of audio-frequency alternating current, and means for coupling 75 said source to the grid of said modulator tube, whereby the oscillator tube is positively modulated at the frequency of said source.

2. A wave signaling system comprising a vacuum tube oscillator having input and output circuits, a modulator tube having input and output circuits, the output circuits of both tubes being conductively connected and supplied from a rectifying device, an audio-frequency alternating current generator arranged to energize said rectifier, means for coupling the generator to the input circuit of the modulator tube, and a keying device in circuit with said coupling means.

In testimony whereof I affix my signature.

DR. ING. LUDWIG KÜHN.
